UNITED STATES PATENT OFFICE.

ABRAM W. WHEATON, OF NEWARK, NEW JERSEY, ASSIGNOR OF ONE-HALF
TO MATTHIAS WHEATON, OF SAME PLACE.

STAIR-ROD SECURER.

SPECIFICATION forming part of Letters Patent No. 349,550, dated September 21, 1886.

Application filed March 11, 1886. Serial No. 194,794. (No model.)

To all whom it may concern:

Be it known that I, ABRAM W. WHEATON, a citizen of the United States, residing in Newark, Essex county, New Jersey, have invented certain new and useful Improvements 5 in Stair-Rods, fully described and represented in the following specification and the accompanying drawings, forming a part of the same.

This invention consists in a stair-rod constructed with transverse holes near the ends and set-screws applied to the ends and intersecting the holes.

In the drawings, Figure 1 is a perspective view of stairs having thereon a carpet with 15 the stair-rods applied thereto. Fig. 2 is a perspective view of one of the stud-brackets to which the ends of the stair-rod are attached. Fig. 3 is a view of the inner side of one end 20 of a stair-rod. Fig. 4 is a longitudinal section through the center of the transverse hole in the rod, and Fig. 5 a similar section showing another construction for the rod. Fig. 6 is a transverse section of the parts shown in Fig. 1 through the transverse hole in the rod. Fig. 7 25 is a section on line $\alpha\alpha$ in Fig. 4. Fig. 8 is a view of a rod in a plane perpendicular to the transverse holes, and Fig. 9 is a view of the same in a plane parallel to the transverse holes, one end being in section. Figs. 3 to 7, including 30 sive, are drawn full size.

The rod itself consists, as shown in Figs. 8 and 9, of a straight bar, C, provided near each end with a transverse hole, c, adapted to receive a stud affixed to the stairs, and having 35 a set-screw, e, inserted in the end of the rod, and extended to such transverse hole to clamp such stud. Figs. 1 and 6 show the application of such rod to the stairs. In these figures, A represents the stairs, and B a carpet secured 40 thereon by two stair-rods, C.

A construction partly of wood and partly of metal is shown in the remaining figures of the drawings for the purpose of furnishing a lighter rod when desired. In these figures, a 45 is the body of the rod, represented herein as of wood, and having a sheet-metal covering, a', secured to its outer surface by bending a flange of the metal into a groove, a², formed on its rear side. A casting, b, is secured at each end 50 of the rod and provided with a transverse

hole, c, and a threaded hole is formed in the end of each casting, intersecting the hole c, and is provided with a set-screw, e. The castings b may be soldered to the sheet-metal covering where it laps over the castings, as 55 shown in Fig. 3; or they may be constructed with a tongue, i, provided with screw-holes and secured by screws s in a slot in the wood beneath the cover, as shown in Figs. 4 and 7.

Such a stair-rod is secured to the stairs by 60 means of studs d, which may be projected diagonally from the angle formed by the tread and riser of the stairs, by any convenient fastening, as the angle-plate f, the studs being secured upon the stairs to coincide with the 65 transverse holes c, formed near the opposite ends of the stair-rod, and the rod being clamped upon the stud, when applied thereto, by turning the set-screws and pinching the studs in the holes c. Such a mode of fastening 70 obviously renders the stair-rod adjustable to and from the angle of the stairs, and permits the rods to be pressed more or less firmly upon the carpet, as may be desired.

The stair-rod may be removed by simply 75 loosening the set-screws in the opposite ends of the same.

In Figs. 1, 3, and 4 the threaded hole is shown formed in its outer end with a cylindrical socket, m, and the head e' of the set-screw is shown constructed like the knob of an acorn, with its base fitted into such socket, so that the screw may be turned in and out without exposing its thread. A similar construction for the set-screw is shown in Figs. 85 8 and 9. By this means the application of the set-screw to the casting b or rod C is entirely concealed.

D in Figs. 4 and 5 represents the line of the step to which the foot of the stud is fastened, 90 and as the screw, when extended in a line with the stair-rod, as shown in Fig. 4, may be difficult of access, I have devised the construction shown in Fig. 5, where the set-screw is inclined to the line of the rod, and therefore 95 stands farther from the step D.

By my construction the metallic ends may be connected with the wood independent of the covering, and the covering may therefore be removed and replaced by another of dif- 100

ferent design when any change occurs in the prevailing style of such articles. Entirely new stair-rods may also be applied to the studs when the latter are once affixed in the stairs.

5 I am aware that a rod having transverse holes near its ends is not new; but such rod has heretofore been secured to the stairs by locking devices attached to the stairs and projecting through the transverse holes therein.

10 I therefore disclaim such construction, limiting myself to the construction shown herein, in which the fastening device is carried by the rod.

Having thus set forth my invention, I claim
15 the same as follows:

1. The combination, with a stair-rod having

transverse holes near the ends and set-screws at the ends, as described, of studs projecting from the stairs, as and for the purpose set forth.

2. The combination, with a stair-rod having
20 transverse holes near the ends and set-screws at the ends, as described, of a stud provided with an angle-plate at its foot, adapted to fit the angle between the tread and riser of the stairs, as and for the purpose set forth. 25

In testimony whereof I have hereunto set my hand in the presence of two subscribing witnesses.

ABRAM W. WHEATON.

Witnesses:
